(57) **CLAIM**

The ornamental design for a kettle device, as shown and described.

DESCRIPTION

FIG. 1 is a back-left perspective view of a kettle device;
FIG. 2 is a front view of the kettle device of FIG. 1;
FIG. 3 is a back view of the kettle device of FIG. 1;
FIG. 4 is a right-side view of the kettle device of FIG. 1;

FIG. 5 is a left-side view of the kettle device of FIG. 1;
FIG. 6 is a top view of the kettle device of FIG. 1;
FIG. 7 is a bottom view of the kettle device of FIG. 1;
FIG. 8 is a back-right perspective view of the kettle device of FIG. 1 with the lid in a closed position;
FIG. 9 is a back-right perspective view of the kettle device of FIG. 1 with the lid in an open position;
FIG. 10 is an exploded perspective view of the kettle device of FIG. 1;
FIG. 11 is a perspective view of the kettle of the kettle device of FIG. 1 shown separately for clarity of illustration of the claim;
FIG. 12 is a front view of the kettle of the kettle device of FIG. 1 shown separately for clarity of illustration of the claim;
FIG. 13 is a back view of the kettle of the kettle device of FIG. 1 shown separately for clarity of illustration of the claim;
FIG. 14 is a right-side view of the kettle of the kettle device of FIG. 1 shown separately for clarity of illustration of the claim;
FIG. 15 is a left-side view of the kettle of the kettle device of FIG. 1 shown separately for clarity of illustration of the claim;
FIG. 16 is a top view of the kettle of the kettle device of FIG. 1 shown separately for clarity of illustration of the claim;
FIG. 17 is a bottom view of the kettle of the kettle device of FIG. 1 shown separately for clarity of illustration of the claim;
FIG. 18 is a perspective view of the base of the kettle device of FIG. 1 shown separately for clarity of illustration of the claim;
FIG. 19 is a front view of the base of the kettle device of FIG. 1 shown separately for clarity of illustration of the claim;
FIG. 20 is a back view of the base of the kettle device of FIG. 1 shown separately for clarity of illustration of the claim;
FIG. 21 is a right-side view of the base of the kettle device of FIG. 1 shown separately for clarity of illustration of the claim;
FIG. 22 is a left-side view of the base of the kettle device of FIG. 1 shown separately for clarity of illustration of the claim;
FIG. 23 is a top view of the base of the kettle device of FIG. 1 shown separately for clarity of illustration of the claim;
and,

(Continued)

FIG. 24 is a bottom view of the base of the kettle device of FIG. 1 shown separately for clarity of illustration of the claim.
